United States Patent Office

Des. 175,269
Patented Aug. 2, 1955

175,269

PAIR OF SPECTACLES

Ella Nelson, Milwaukee, Wis.

Application October 8, 1954, Serial No. 32,595

Term of patent 14 years

(Cl. D57—1)

Fig. 1 is a view in perspective of a pair of spectacles, showing my new design.

Fig. 2 is a top plan view of the same.

I claim:

The ornamental design for a pair of spectacles, as shown.
